FLASHLIGHT HOLDER

Richard Micek, Walsenburg, Colo.

Application August 16, 1948, Serial No. 44,551

2 Claims. (Cl. 248—166)

1

This invention relates to an improved flashlight holder especially designed for use as an automobile accessory although, however, the device will be found convenient and adaptable for home use, or in any other instance where it may be desired to adjustably support a conventional flashlight so that the beam thereof may be trained upon the work at hand.

The objects of the invention are to provide a holder adapted to serve as a stand for the flashlight, wherein the flashlight may be adjustably tilted upon the stand to direct the beam of the flashlight either up or down as may be desired, wherein the stand will embody a substantially semi-circular sleeve to removably accommodate the flashlight, wherein said sleeve will be composed of a pair of jaws so connected that the presence of the flashlight between the jaws will serve to tension the connection coupling the jaws so that the jaws will thus be caused to grip the flashlight, wherein each jaw will carry a pair of coacting foldable legs, and wherein the jaws may be readily separated so that the device may be collapsed to form only two major sections which may be packed in minimum space and, if so desired, carried in the usual glove compartment in the dash of an automobile.

Other and incidental objects will appear during the course of the following description of the invention, and in the drawings:

Figure 1 is a perspective view of my improved flashlight holder showing, in dotted lines, a conventional flashlight in position thereon.

Figure 2 is a plan view of the holder.

Figure 3 is a side elevation.

Figure 4 is an end elevation.

Figure 5 is a section on the line 5—5 of Figure 2, the flashlight being shown.

Figure 6 is an inverted perspective view of the two jaws of the flashlight gripping-sleeve of the device.

Figure 7 is a fragmentary section showing the connection between one of the sleeve-jaws and its pair of legs, the parts being separated.

Figure 8 is a fragmentary elevation of the head of one of the legs.

Figure 9 is a fragmentary section showing a modification of the connection seen in Figure 7.

In carrying the invention into effect, I employ a substantially semi-circular sleeve, indicated as a whole at 10. This sleeve comprises, as best seen in Figure 6 of the drawings, a pair of companion jaws 11 and 12 respectively, each more or less arcuate in cross section. These jaws are preferably stamped from suitable resilient sheet

2

metal, and adhesively or otherwise secured to the inner sides thereof near the ends of each jaw are pads 13 of felt or the like.

As perhaps best shown in Figure 5 of the drawings, the lower margins of the jaws 11 and 12 extend somewhat tangentially to the curvature of said jaws, and formed on the lower edge of the jaw 11 are straight longitudinally spaced tongues 14 which are resilient, while the jaw 12 is provided at its lower margin with a corresponding number of mating slots 15 adapted to removably receive said tongues. The jaws are assembled by first swinging the upper longitudinal margins of the jaws toward each other so that the tongues 14 may be freely inserted through the slots 15, after which the jaws are swung apart to form the sleeve 10. A freely separable connection is thus provided between the jaws.

Each of the jaws 11 and 12 carries a pair of mating legs comprising an inner leg 16 and an outer leg 17, both preferably stamped from suitable resilient sheet metal. The leg 16 is formed at its upper end with a head 18 and at its outer longitudinal edge with a flange 19, while the leg 17 is formed at its upper end with a head 20 and at its inner longitudinal edge with a flange 21. Formed in the lower ends of both legs are openings 22.

As the connections between the pairs of legs 16 and 17 and the jaws 11 and 12 are alike, only one need be described, the jaw 11 being chosen. Formed in the upper margin of said jaw medially thereof is a circular bearing 23 having a plurality of radial ribs 24. The head 18 of the coacting leg 16 is provided with a similar bearing 25 having like radial ribs 26, and extending freely through said bearings as well as through the head 20 of the coacting leg 17 is a pivot bolt 27 preferably provided with a wing nut 28. Interposed between said nut and the head 20 is a spring 29. Thus, the nut 28 may be tightened to tension the spring 29 and clamp the parts together, the spring being adapted to accommodate relative swinging movement of the legs 16 and 17 so that the ribs 26 may ride over the ribs 24. Normally, however, the ribs will serve to releasably lock the legs in angular adjusted position.

It is now to be noted, say in connection with the jaw 11 as typical, that when the legs 16 and 17 thereof are swung apart, the forward inner edge of the head 20 of the leg 17 is, as best seen in Figures 1 and 3 of the drawings, adapted to engage the upper end of the flange 19 of the leg 16 for limiting the legs in angular spread position so that the legs may not move

apart into aligned collapsed relation. However, as will be appreciated, the legs may be swung together into overlapping folded relation, when the flange 21 of the outer leg 17 will abut the flange 19 of the inner leg 16 for limiting the legs in folded position.

As particularly seen in Figures 1 and 5 of the drawings, the sleeve 10 is adapted to removably accommodate a flashlight, conventionally shown at 30. The jaws 11 and 12 of the sleeve are so fashioned that the flashlight may be inserted between the upper edges of said jaws and pressed downwardly to rest between the jaws upon the pads 13 to be protected against scuffing thereby. Moreover, the presence of the flashlight between the jaws will serve to spread the jaws apart somewhat, with the result that the tongues 14 of the jaw 11 will be flexed and thus tensioned in the slots 15 of the jaw 12. The tongues will accordingly serve not only to detachably connect the jaws, as previously described, but also, as resilient elements functioning to clamp the flashlight 30 between the jaws.

Having positioned the flashlight 30 in the sleeve 10, the legs 16 and 17 of the respective pairs thereof may be spread apart to provide a stand for supporting the flashlight upon a roadway, for instance, in convenient position, so that say a tire may be changed or other repairs made, in the beam from the flashlight. As will be perceived, the flashlight may be adjustably swung about the axis of the bolts 27 either up or down so that the beam from the flashlight may be directed upon the exact spot desired. In this connection, it is also to be noted that the holes 22 in the legs 16 and 17 provide a means whereby, through the medium of any one of said holes, the stand and flashlight may be hung upon a branch of a bush or the like, when the flashlight may be adjusted as desired.

As previously pointed out, the presence of the flashlight 30 between the jaws 11 and 12 binds the jaws together to provide the stand for the flashlight and, as will now be perceived, this stand is formed of mating detachably connected sections each comprising a jaw and a pair of foldable legs as, for instance, the jaw 11 and its pair of legs 16 and 17. Thus, after the flashlight is removed, the jaws may be separated, when the folded legs of each jaw may be swung into parallel relation thereto. The two separated sections may accordingly be brought to-

gether to occupy small space and, if so desired, packed in the glove compartment of an automobile along with the flashlight.

In Figure 9 of the drawings, I have shown a slight modification in the connection between a pair of legs and their coacting jaw. A simple rivet 31 is employed in lieu of the parts 27 and 28, while a cupped resilient washer 32 is employed in lieu of the spring 29 to serve the purpose of said spring.

Having thus described my invention, I claim:

1. A flashlight holder including companion jaws adapted to receive a flashlight therebetween, means detachably connecting said jaws with each other and tensioned by spreading of the jaws by the flashlight to grip the flashlight between the jaws, a pair of swingingly adjustable legs carried by each jaw, the legs of said pairs being adapted to be spread apart to form a stand for the flashlight, flanges on said legs for limiting the legs of each pair in folded overlapping relation, and a head carried by one leg of each pair to engage the flange of the other leg of each pair for limiting the legs of the pairs in spread position.

2. A flashlight holder including a stand comprising a sleeve adapted to receive a flashlight therein and formed of companion jaws, legs pivotally connected to said jaws and supporting the sleeve for swinging adjustment to tilt the flashlight, and means slidably connecting the jaws with each other and freely separable to permit the stand to be collapsed in mating sections each comprising a jaw and leg.
